UNITED STATES PATENT OFFICE.

AMMI B. BENJAMIN, OF KELLOGGSVILLE, OHIO.

SPARK-ARRESTER.

SPECIFICATION forming part of Letters Patent No. 307,165, dated October 28, 1884.

Application filed March 15, 1883. (No model.)

To all whom it may concern:

Be it known that I, AMMI B. BENJAMIN, a citizen of the United States of America, residing at Kelloggsville, in the county of Ash-5 tabula and State of Ohio, have invented cer-10 tain new and useful Improvements in Spark-15 Arresters; and I do hereby declare the fol-20 lowing to be a full, clear, and exact descrip-25 tion of the invention, such as will enable oth-30 ers skilled in the art to which it appertains 35 to make and use the same, reference being had to the accompanying drawing, and to letters or figures of reference marked thereon, which form a part of this specification.

15 This invention relates to that class of spark-30 arresters in which a body of water is arranged to catch the sparks, which are carried into it by suitable deflectors of the draft.

20 The object of my invention is to simplify 25 the construction of this class of spark-ar-30 resters and render them more efficient and re-35 liable than heretofore; and with these objects 40 in view my improvement consists in certain 45 novel constructions and combinations of parts, 50 which will be hereinafter particularly de-55 scribed, and pointed out in the appended 55 claim.

30 In the accompanying drawing the figure is 35 a vertical section of a smoke-stack and spark-40 arrester constructed according to my invention.

45 My spark-arrester is intended especially for 50 use in connection with farm or road engines 55 and the like, but may of course be used in 60 connection with any apparatus to which such 65 a device is applicable.

40 In the drawing, D designates the upper part 45 or head of the smoke-stack, under which is 50 the cylindrical portion D', hinged to the smoke-55 box in the usual manner, and connected with 60 the flaring or funnel-shaped portion D'', a 65 curved angular deflector or flange, I, sur-70 rounding the head and supporting the central 75 tube, J, which extends slightly into the 80 head a few inches, has its lower end project-85 ing below the same. Within the flaring por-85 tion D'' of the stack is centrally arranged a 90 reservoir, E, the lower portion of which has 95 the form of an inverted cone, while its upper 95 portion is cylindrical and surrounds the 100 lower end of the pipe J, being separated there- 100 from by an intervening space, which is about

equal in width to that of the space between 55 all parts of the reservoir and the smoke- 55 stack, this space forming an annular flue, A.

L indicates the exhaust-pipe, which termi- 55 nates in the smoke-stack directly under the 55 pointed lower end of the reservoir.

G is a supply-pipe through which water 60 may be furnished to the reservoir, and H is 65 an overflow-pipe by which the water in the 70 reservoir is prevented from rising higher than 75 a proper level. The inner rim or flange, M, 80 on the upper edge of the reservoir prevents 85 the water from splashing over into the flue A.

70 The operation of the apparatus is as fol- 75 lows: The blast from the exhaust-pipe L drives 80 the smoke and sparks forcibly upward through 85 the flue A, surrounding the reservoir E, and 90 the sparks striking the deflector I are carried 95 against the pipe J and into the water W, 100 while the smoke rises and passes off through 105 the pipe J. The upper portion of the stack, 110 which carries the flange I and pipe J, is 115 connected by a slip-joint at d to the lower por- 120 tion, so that it may be readily removed there- 125 from to permit the reservoir to be inserted 130 or removed, said reservoir being held in place 135 by suitable braces, as shown.

140 I am aware that smoke-stacks have been 80 provided with annular reservoirs through the 85 center of which the draft passes and is de- 90 flected thereinto by suitable deflecting-plates, 95 and I lay no claim to such construction.

What I claim is—

85 The combination, in a spark-arrester, of a 90 smoke-stack, D, having the cylindrical por- 95 tion D', flaring portion D'', and inward and 100 downward bent flange I, of the smoke-pipe J, 105 secured to said flange and within the central 110 opening surrounded by the same and project- 115 ing below said flange, and of the conical reser- 120 voir E, removably arranged within the smoke- 125 stack and provided with a rim, M, and hav- 130 ing its open upper end terminating under said 135 flange and surrounding the lower portion of 140 the pipe J, substantially as set forth.

145 In testimony whereof I affix my signature in 150 presence of two witnesses.

AMMI B. BENJAMIN.
